UNITED STATES PATENT OFFICE.

GEORGE WALTER ADAMS, OF EAST TAWAS, MICHIGAN.

VALVE.

No. 800,782.

Specification of Letters Patent.

Patented Oct. 3, 1905

Application filed December 1, 1904. Serial No. 235,111.

To all whom it may concern:

Be it known that I, GEORGE WALTER ADAMS, a citizen of the United States, residing at East Tawas, in the county of Iosco and State of Michigan, have invented certain new and useful Improvements in Valves; and I do declare the following to be a full, clear, and exact description of the invention, such as will enable others skilled in the art to which it applies to make and use the same.

My invention relates to improvements in valves, and more particularly to a quick opening and closing pressure-valve.

The object of my invention is to improve and simplify the construction and operation of devices of this character, and thereby render the same more efficient and durable in use and less expensive to manufacture.

With the above and other objects in view the invention consists of certain novel features of construction, combination, and arrangement of devices hereinafter described and claimed.

In the accompanying drawings, Figure 1 is a sectional view through a valve constructed in accordance with my invention. Fig. 2 is an elevation, partly in section, taken on the line 2-2 of Fig. 1. Fig. 3 is a top plan view.

Referring to the drawings by numeral, 1 denotes a valve-casing, which may be of any suitable form and construction and which is provided within the same with a valve-seat 2. Coacting with said valve-seat is a valve 3, which is, as shown in Fig. 1, adjustably secured upon the valve-stem 4, which is slidably mounted in the casing 1 and projects through its top or cover 5.

As clearly shown in Fig. 1 of the drawings, the adjustable connection between the valve 3 and its stem 4 is formed by providing upon the latter two screw-threaded portions 6 and 7, which are preferably of different diameters, and confining the said valve 3 between two nuts 8 and 9, which are screwed upon said screw-threaded portions 6 and 7 above and below the said valve. By this construction it will be seen that the valve 3 may be readily adjusted longitudinally upon the valve-stem 4 in order to cause it to properly engage the valve-seat 2.

Upon the outer face of the top or cover 5 of the valve-casing is secured a guard ring or plate 16, which alines with the opening 17 in

said top, through which the outer portion of the valve-stem 4 projects, and above said ring or plate 16 are bolted or otherwise secured to the top 5 two angular bracket-arms 18, which have their upper ends bent in parallel relation and disposed in alinement with the axis of the valve-stem. Between the said ends of the bracket-arms 18 is pivoted, by a bolt 19 or the like, a right-angularly-shaped operating-lever 20. The said lever is thus pivoted at its angle and has its short arm or end 21 pivotally connected by a pair of links 22 to the upper end of the valve-stem 4. The long end or arm 23 of said operating-lever is adapted to engage a stop 24 when said lever, and hence the said valve, is in its closed or locked position. The stop 24 is in the form of an angular bracket, which is secured upon the top 5 adjacent to its edge, as shown. The relative length of the valve-stem, the links 22, and the arm 21 of the lever 20 is such that when the other end 23 of said lever is swung downwardly into engagement with the bracket 24 the small end 21 of the lever will pass beyond the center of the pivot 19 of said lever to cause the latter, and hence the valve, to be locked in its closed position, as will be readily seen upon reference to Fig. 1 of the drawings, the parts being shown in their locked position in dotted lines and in their open position in full lines.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

A valve comprising a casing having a removable cap at its upper end and provided with an interior valve-seat, a valve-stem guided and having longitudinal movement in the cap and extending into said casing, a valve carried by the valve-stem adjustable thereon and coacting with the valve-seat, bracket-arms on the cap, a right-angular lever pivoted between said arms, a link connecting

the shorter arm of said lever to the valve-
stem and a stop on the cap coacting with the
longer arm of the lever to retain the valve-
stem and valve in operative position, the
5 valve, valve-stem, stop, lever and link being
removable from the casing with the cap.

In testimony whereof I have hereunto set

my hand in presence of two subscribing wit-
nesses.

GEORGE WALTER ADAMS.
